CIRCULAR KNITTING MACHINE

Thomas Charles Bromley and Arthur Shortland,
Leicester, EnglandApplication October 1, 1942, Serial No. 460,429
In Great Britain October 20, 1941

13 Claims. (Cl. 66—150)

This invention relates to circular knitting machines of the kind adapted to produce tubular knitted fabric or strings of articles with pouches.

The invention is applicable with advantage to circular rib knitting machines for producing ribbed or partly ribbed articles of footwear in the knitting of which difficulty is normally experienced in producing clear rib knitting following the formation of a pouch. This is so, for instance, in the knitting of a rib top following the formation of a toe pouch. It is found that due to the unequal pull of the take-up mechanism on the work, owing to the presence of a pouch formed immediately preceding production of rib fabric, loop accumulation or tucking is apt to occur when rib knitting is commenced after formation of the pouch.

Accordingly, the principal object of the present invention is to provide improved means designed to obviate the foregoing disadvantage by tensioning the work after formation of a pouch.

It is principally the intention to apply the invention to circular knitting machines of the double axially opposed needle cylinder type adapted to produce articles comprising rib tops, leg and foot portions, and heel and toe pouches as the result of continuous operation. The invention may, however, be usefully applied to other circular knitting machines of the kind concerned—rib and plain.

Broadly considered, the improved tensioning means include a fabric engaging member or members which or each of which is adapted, upon being engaged with an appropriate portion of the work during the formation or after the completion of a pouch, to move as knitting proceeds suchwise as to enable its operative extremity to conform to the path followed by the fabric as it leaves the needles.

The principal aim, then, is the provision of a fabric engaging member or members which or each of which, when in engagement with a portion of the knitted fabric following a completed pouch, has a movement, in addition to being moved bodily in a direction necessary to apply tension to the work between the pouch and the knitting needles, whereby the operative end of the member closely follows the aforesaid path and thereby effectively tensions the work as it is drawn off the needles through the needle cylinder, or the appropriate needle cylinder, as the case may be.

Particular illustrative examples of the invention as applied to a machine of the characteristic type having superimposed rotary needle cylinders

will now be described with reference to the accompanying drawings, wherein,

Figure 1 is a vertical sectional view of so much of the said machine as is necessary to illustrate the application thereto of one form of the improved tensioning means including a circular series of fabric engaging members,

Figure 2 is a detail plan view depicting the layout of the said members,

Figure 3 is a view similar to Figure 1 illustrating another example embodying a single fabric engaging member,

Figure 4 is a plan view partly in section taken on the line IV—IV of Figure 3 showing this member and also the carrier disc upon which it is mounted, and

Figures 5 and 6 are two views somewhat similar to Figures 3 and 4 respectively showing a modification in which a single fabric engaging member is actuated through the medium of rack and pinion mechanism.

Like parts are designated by similar reference characters throughout the drawings.

In Figure 1, the upper portion of the bottom or plain cylinder of the machine is indicated at 2, whereas the lower portion of the axially opposed rib cylinder component is shown at 3. In accordance with customary practice, the machine is equipped with inside sinkers or web holders, such as 4, which are mounted within a sinker ring or bed 5 secured to the bottom or plain cylinder 2. The sinkers or web holders are operated by cams held in position by a sinker cup 6 of conventional form. This cup has a curved surface 6a to support the fabric f as it leaves the needles—portions of which latter are indicated diagrammatically at 7. A cylindrical part 8 constituting a verge is mounted within the lower end of and adapted to rotate with the rib cylinder 3. The verge 8 is adjustable axially for which purpose it is carried by a central tube 9 movable up and down within the rib cylinder, e. g., by a lever (not shown) under suitable automatic control. But although it is movable axially, the verge tube 9 is fixed so far as rotary movement is concerned. A ball bearing 10 is accordingly provided in the manner shown between the verge and the verge tube and the latter is secured at its lower end to the ball race cover 11. The underside of the verge is recessed at 8a.

In accordance with the present invention a circular series of fabric engaging elements 12 located on the inside of the needle circle is provided. These elements are in the form of levers pivotally mounted at their inner ends in an ap-

propriately grooved circular carrier 13, each of the said elements being accommodated within one of the vertical grooves 13a. A ring 14 secured in an annular groove 15 formed in the carrier 13 near the lower end thereof constitutes a common member upon which the fabric engaging elements 12 are arranged to pivot (see, more particularly, Figure 2). The circular carrier 13 is attached to or formed integrally with the lower end of a square rod 16 which extends downwardly into the plain cylinder component concentrically therewith and is slideable through the verge tube 9 for causing the fabric engaging elements 12 to apply tension to the work in the required manner, and for restoring the carrier to its normal inoperative position at appropriate times. For the sake of convenience in illustration, the carrier 13 is shown in two halves in Figure 1, the left-hand half being raised with the fabric engaging elements in their normal inoperative positions and the right-hand half being depressed with the said elements in contact with the fabric *f*. Secured to the underside of the verge 8 is a longitudinally grooved cam part 17 of downwardly tapered form having a slightly outwardly curved surface. An axial hole 18 is formed in this cam part to enable the rod 16 to pass downwardly right through it, the lower portion of the hole being reduced and made square at 18a to afford support and guidance for the said rod. The cam part 17, moreover, is formed with a series of radially disposed grooves 19 each for accommodation of the upper end of one of the pivoted fabric engaging elements 12. That is to say, in their normal inoperative positions, the elements 12 project up through the grooves 19 with their rear edges 12a in contact with the outwardly curved backs or bottoms of the grooves 19. As will be seen in Figure 1, the said grooves are of uniform depth but, owing to the form of the cam part 17, are inclined so as to converge in a downward direction towards the central longitudinal axis *a* of the machine. The upper, i. e., operative, extremities of the lever-like elements 12 may conveniently be formed to provide spatulate presser feet 12b for engagement with the work (see Figure 2). Between their ends the elements are notched or recessed for reception of an annular spring band 20 which surrounds the elements and serves to maintain their rear edges 12a in engagement with the backs or bottoms of the grooves 19. The rear edge 12a of each element is curved suchwise as to provide a cam formation for contact and co-operation with the outwardly curved back or bottom of the corresponding groove in the cam part 17. The carrier 13 is normally held up in contact with the bottom of the cam part at such a height or level that the presser feet 12a are disposed well up in the recess 8a beneath the verge 8—clear of the fabric *f*, as shown at the left-hand side of Figure 1. When, however, the rod 16 is caused to move downwards through the central verge tube 9 and the cam part 17, the rear edges 12a of the fabric engaging elements 12 slide over the curved backs or bottoms of the corresponding grooves 19 with the result that the elements are permitted to turn on the pivot ring 14 under the influence of the annular spring band 20, whereby the presser feet swing inwards and are thus enabled to conform closely to the contour of the sinker cup 6 as they come into contact with and apply tension to the work. During such downward movement

of the rod 16 the elements 12 are withdrawn from the grooves 19 and consequently from the control of the cam part 17, whereupon their inward turning movement is arrested by reason of their rear edges coming into contact with the backs or bottoms of the grooves 13a in the carrier 13, as shown at the right-hand side of Figure 1.

Conversely, as the rod 16 is raised again, the fabric engaging elements 12 re-enter the grooves 19 and are gradually cammed out against the spring action until they assume their inoperative positions. The rod 16 is adapted to be automatically operated and controlled from the main timing or controlling mechanism of the machine, or from a subsidiary mechanism controlled by or from the main mechanism, for example through the medium of levers or/and linkage or equivalent intermediate connections. The rod and the associated operating and controlling means are preferably loaded, e. g., by spring means, so as to enable the tension to be yieldingly applied.

When restoring the carrier 13 to its normal raised position, care must, of course, be taken to ensure that the presser feet 12a do not drag upon and thereby cause damage to the fabric *f*. To guard against this the presser feet may themselves be made yieldable. Alternatively, they may be moved clear of the fabric prior to upward movement of the rod.

In the further example illustrated in Figures 3 and 4, a single fabric tensioning member 21 of mainly rectangular form is employed. As shown in Figure 4, however, the serrated operative extremity 21a of this member is curved and splayed outwardly and bent downwards somewhat. The member is slidably mounted upon a carrier disc 22 which latter is secured to the lower end of a square section operating rod 16. The carrier disc may (as shown) or may not itself also be adapted to function for fabric tensioning purposes. The inner end of the slideable tensioning member 21 is forked at 21b to accommodate the rod 16 and the said member is arranged to slide between a pair of screws 23 (or equivalent) appropriately disposed on the carrier disc 22. As will be seen in Figure 3, the operating rod 16 passes up through a square hole formed in a washer 24 secured to the underside of the axially adjustable verge 8, so that the tensioning member 21 is maintained in correct relation to pouch fabric being knitted. As in the previously described example, the verge is provided with a co-axial verge tube 9 and the operating rod extends up through this tube and is subject to suitable automatic control. Secured to the verge 8 is a cam or like part such as 25 which extends through a slot 21c in the slideable tensioning member 21. Normally the last mentioned member and its carrier disc 22 are located closely beneath the verge in the recess 8a with the tensioning member projected well beyond the inner wall of the sinker cup 6 as indicated in full lines in Figure 3. Immediately upon a pouch being knitted, however, the operating rod 16 together with the carrier disc 22 is lowered to bring the fabric tensioning member 21 into engagement with and to apply tension to the appropriate portion of the knitted fabric *f*, whereupon the said member is simultaneously caused to slide radially inwards by action of the cam or like part 25 within the slot 21c. The lowered position of the disc 22 is indicated in dot-and-dash lines in Figure 3.

To enable the described movements to take place, the forward portion of the carrier disc 22 has formed therein an open-ended slot 22a to receive the cam or like part 25. Thus, by reason of the rod being lowered the fabric engaging member 21 has imparted thereto a compound movement the initial stage of which brings it into engagement with the work after which the member, still sliding inwards until it is just within the inner wall of the sinker cup 6, conforms to the path followed by the fabric leaving the needles. Upon the parts being restored to their inoperative position by raising the operating rod, the slidable fabric engaging member 21 is automatically projected radially outwards, by the cam or like part 25, in readiness for further use. To effect the required sliding movements of the fabric engaging member, in a positive manner, the cam or like part may, as shown, be so shaped as to have a straight inwardly inclined portion 25a, a downwardly directed portion 25b and an intermediate curved portion 25c.

According to the still further example illustrated in Figures 5 and 6, the fabric tensioning means comprise a single member 26 which is adapted to be actuated by a suitably controlled operating rod 27 through the medium of rack and pinion mechanism. The tensioning member 26 is attached to two parallel guide bars 28 and 29 which are supported between spaced carrier discs 30 and 31 secured upon the operating rod 27. The guide bars 28 and 29 are arranged to slide between pairs of small rollers 32 carried by the spaced discs. Moreover, at its inner end each of the guide bars is formed with a shoulder 33 designed to come into contact with one of the rollers 32 to limit outward sliding movement of the tensioning member 26 at appropriate times. The operating rod 27 extends vertically downwards into the bottom or plain cylinder 2 of the machine through a verge tube 34 mounted coaxially upon the adjustable top verge 8 associated with the top or rib cylinder 3. A guide rod 35 depending from the said verge and extending through the carrier discs 30 and 31 serves to prevent turning motion of the latter and thereby maintains the slidable tensioning member 26 in correct relation to pouch fabric being knitted. A nut 36 which is screwed onto the lower end of the verge tube 34 is located beneath the top verge 8 for a purpose hereinafter to be explained. The underside of the said top verge is recessed at 8a and normally accommodates the carrier discs and tensioning member. The inner side of the guide bar 29 is toothed to provide a rack for co-operation with a pinion 37 mounted to turn freely upon the operating rod 27. A screw 38 formed integrally with or rigidly secured to this pinion 37 is engaged with a nut 39 having a "multi-start" thread. As will be seen in Figure 5, this nut is pinned by means of a cotter pin 40 to the lower end of the operating rod 27. The construction and arrangement is such that upon the operating rod being depressed the carrier discs 30 and 31 are lowered until the tensioning member 26 rests on the fabric. Further depression of the rod will thereupon cause the nut 39 with multi-start thread to rotate the screw 38 and hence also the pinion 37 so that the tensioning member 26 will slide radially inwards to follow the path of the fabric. When, however, the carrier discs and the tensioning member are again restored to normal inoperative position within the recess 8a in the top verge, by raising the operating rod 27, the pinion 37

abuts against the nut 36 on the verge tube 34. Consequently, further upward movement of the operating rod causes the multi-start nut to turn the pinion in the reverse direction so that the tensioning member is caused to slide radially outwards.

In either of the last two described examples more than one slidable tensioning member may, if desired, be provided.

10. What we claim then is:

1. In a circular knitting machine of the kind herein referred to, in combination, a cylinder, needles in said cylinder, a plurality of movable fabric engaging members the operative extremities of which are directed towards the needles, a common carrier for said members, means for moving the carrier axially within the needle cylinder, and means for effecting inward radial movement of said members on the inside of the needle circle, conjointly with axial movement of the carrier, as knitting proceeds, whereby the operative extremities aforesaid have imparted to them a compound movement conforming with the path followed by the work as it leaves the needles, for the purpose of applying tension to said work.

2. In a circular knitting machine of the kind herein referred to, in combination, a cylinder, needles in said cylinder, a sinker ring associated with the cylinder, arcuate inside sinkers mounted in said ring, a sinker cup for holding cams for operating the sinkers, said cup having a curved fabric-supporting surface, a circular series of fabric tensioning members the operative ends of which are normally directed towards the needles, a carrier wherein the said members are pivotally mounted, a rod movable axially within the needle cylinder and to which the carrier is attached, a relatively fixed cam part having therein longitudinal grooves through which the fabric tensioning members extend, and spring means for normally maintaining the said members in contact with the cam part, the construction and arrangement being such that when the rod is moved axially in the appropriate direction within the needle cylinder to effect application of tension to the work as it is drawn off the needles, the rear edges of the fabric tensioning members slide over the backs of the aforesaid grooves with the result that the members are permitted to turn the influence of the spring means suchwise that their operative ends swing inwards and thereby have a compound movement conforming with the contour of the fabric-supporting surface of the sinker cup, for the purpose herein specified.

3. In a circular knitting machine of the kind herein referred to, in combination, a plain needle cylinder, an axially opposed rib needle cylinder, needles operable in said cylinders, a sinker ring carried by the said plain cylinder, a verge associated with the rib cylinder, arcuate inside sinkers provided in the sinker ring, a sinker cup for holding cams for operating the sinkers, said cup having a curved fabric-supporting surface, a circular series of fabric tensioning members the operative ends of which are normally directed towards the needles, a carrier wherein the said members are pivotally mounted, an operating rod movable along the cylinder axis and to which the carrier is attached, a cam part secured to the underside of the verge and having therein longitudinal grooves through which the fabric tensioning members extend, and spring means for normally maintaining the said members in con-

tact with the cam part, said cam part being formed with an axial hole through which the operating rod extends, the construction and arrangement being such that when the operating rod is moved downwards to effect application of tension to the work as it is drawn off the needles, the rear edges of the fabric tensioning members slide over the backs of the aforesaid grooves with the result that the members are permitted to turn under the influence of the spring means suchwise that their operative ends swing inwards and thereby have a compound movement conforming with the contour of the fabric-supporting surface of the sinker cup.

4. In a circular knitting machine of the kind herein referred to, in combination, a cylinder, needles in said cylinder, a fabric tensioning member the operative extremity of which is directed towards the needles, a disc upon which the said member is slidably mounted, a rod which carries the disc and is movable along the cylinder axis, means for moving the rod axially within the needle cylinder, and means for effecting inward sliding movement of the tensioning member radially on the inside of the needle circle, conjointly with movement of the rod in such a direction as to apply tension to the work, as knitting proceeds, whereby the operative extremity aforesaid has imparted to it a compound movement conforming with the path followed by the said work as it leaves the needles.

5. In a circular knitting machine of the kind herein referred to, in combination, a cylinder, needles in said cylinder, a sinker ring associated with the cylinder, arcuate inside sinkers provided in said ring, a sinker cup holding cams for operating the sinkers, said cup having a curved fabric-supporting surface, a fabric tensioning member the operative portion of which is directed towards the needles, a disc upon which said member is slidably mounted, a rod which carries the disc and is movable along the cylinder axis, means for moving the rod axially within the needle cylinder, and relatively fixed cam means adapted for co-operation with the fabric tensioning member suchwise as to effect an inward sliding movement of the same radially on the inside of the needle circle, conjointly with movement of the rod in such direction as to apply tension to the work, as knitting proceeds, whereby the operative extremity aforesaid has imparted to it a compound movement conforming with the contour of the fabric-supporting surface of the sinker cup.

6. In a circular knitting machine of the kind herein referred to, in combination, a cylinder, needles in said cylinder, a fabric tensioning member which has its inner end forked and its outer operative extremity directed towards the needles, a disc having thereon a pair of elements between which the fabric tensioning member is arranged to slide, a rod which carries the disc and is accommodated in the forked end of the said member, means for moving the rod axially along the cylinder axis, and means for effecting inward sliding movement of the tensioning member radially on the inside of the needle circle, conjointly with movement of the rod in such a direction as to apply tension to the work, as knitting proceeds, whereby the operative extremity aforesaid has imparted to it a compound movement conforming with the path followed by the said work as it leaves the needles.

7. In a circular knitting machine of the kind herein referred to, in combination, a plain needle

cylinder, an axially opposed rib needle cylinder, needles operable in said cylinders, a sinker ring carried by the said plain cylinder, a verge associated with the rib cylinder, arcuate inside sinkers provide in the sinker ring, a sinker cup for holding cams for operating the sinkers, said cup having a curved fabric-supporting surface, a slotted fabric tensioning member which has its inner end forked and its outer operative extremity directed towards the needles, a disc having thereon a pair of elements between which the fabric tensioning member is arranged to slide, a rod which carries the disc and is accommodated in the forked end of the said member, means for moving the rod axially along the cylinder axis, and a cam which is secured to the verge and extends through the slot in the fabric tensioning member, said cam being so formed for co-operation with the said member as to effect an inward sliding movement of the same radially on the inside of the needle circle, conjointly with movement of the rod in such direction as to apply tension to the work, as knitting proceeds, whereby the operative extremity aforesaid has imparted to it a compound movement conforming with the contour of the fabric-supporting surface of the sinker cup.

8. In a circular knitting machine of the kind herein referred to, in combination, a cylinder, needles in said cylinder, a sinker ring associated with the cylinder, arcuate inside sinkers provided in said ring, a sinker cup holding cams for operating the sinkers, said cup having a curved fabric-supporting surface, a fabric tensioning member the operative portion of which is directed towards the needles, a disc upon which said member is slidably mounted, a rod which carries the disc and is movable along the cylinder axis, means for moving the rod axially within the needle cylinder, and rack and pinion means which are so arranged between the rod and the slideable member as to be adapted to effect an inward sliding movement of the same radially on the inside of the needle circle, conjointly with movement of the rod in such direction as to apply tension to the work, as knitting proceeds, whereby the operative extremity aforesaid has imparted to it a compound movement conforming with the contour of the fabric-supporting surface of the sinker cup.

9. In a circular knitting machine of the kind herein referred to, in combination, a cylinder, needles in said cylinder, a sinker ring associated with the cylinder, arcuate inside sinkers provided in said ring, a sinker cup holding cams for operating the sinkers, said cup having a curved fabric-supporting surface, a fabric tensioning member the operative end of which is directed towards the needles, parallel guide bars to which said member is attached and one of which bars is toothed to provide a rack, spaced carrier discs between which said guide bars are slidably supported, an operating rod movable within and axially with respect to the cylinder, a pinion which is mounted to rotate freely upon the rod and adapted for co-operation with the aforesaid rack, a nut which is secured to said rod, and a screw which rotates with the pinion and co-operates with the nut, the construction and arrangement being such that when the operating rod is moved downwards to effect application of tension to the work as it is drawn off the needles, the operative end of the fabric tensioning member has a compound movement conforming with the contour of the fabric-supporting surface of the sinker cup.

10. In a circular knitting machine of the kind herein referred to, in combination, a cylinder, needles for operation in said cylinder, a part by

which fabric is supported and caused to follow an inward path as it leaves said needles, a movable fabric engaging member the operative extremity of which is directed towards the needles, a carrier for said member, means for moving the carrier axially within the needle cylinder to bring the fabric engaging member into engagement with the work and thereupon to cause said member to apply tension to the same, and controlling means for effecting inward radial movement of said member on the inside of the needle circle, conjointly with said axial movement of the carrier, as knitting proceeds, whereby after being engaged with an appropriate portion of the work the operative extremity aforesaid has imparted to it a compound downward and radially inward movement conforming with the aforesaid path followed by the work, for the purpose described.

11. In a circular knitting machine of the kind herein referred to, in combination, a cylinder, needles for operation in said cylinder, a sinker ring associated with the cylinder, inside sinkers mounted in said ring, a sinker cup for holding cams for operating the sinkers, said cup having a fabric-supporting surface whereby fabric is caused to follow an inward path as it leaves the needles, a movable fabric engaging member the operative extremity of which is directed towards the needles, a carrier for said member, means for moving the carrier axially within the needle cylinder suchwise as to bring the fabric engaging member into engagement with the work and thereupon to cause said member to apply tension to the same, and controlling means for effecting inward radial movement of said member on the inside of the needle circle, conjointly with axial movement of the carrier, as knitting proceeds, whereby after being engaged with an appropriate

portion of the work the operative extremity aforesaid has imparted to it a compound downward and radially inward movement conforming with the contour of the fabric-supporting surface of the sinker cup, for the purpose described.

- 5 12. In a circular knitting machine of the kind herein referred to, in combination, a cylinder, needles in said cylinder, a pivotally mounted fabric engaging member the operative extremity of 10 which is directed towards the needles, a carrier for said member, means for moving the carrier axially within the needle cylinder, and means for effecting inward radial movement of said member on the inside of the needle circle, conjointly 15 with axial movement of the carrier, as knitting proceeds, whereby the operative extremity aforesaid has imparted to it a compound movement conforming with the path followed by the work as it leaves the needles, for the purpose of applying 20 tension to said work.
13. In a circular knitting machine of the kind herein referred to, in combination, a cylinder, needles in said cylinder, a slidably mounted fabric engaging member the operative extremity of 25 which is directed towards the needles, a carrier for said member, means for moving the carrier axially within the needle cylinder, and means for effecting inward radial movement of said member on the inside of the needle circle, conjointly with axial movement of the carrier, as knitting proceeds, whereby the operative extremity aforesaid has imparted to it a compound movement conforming with the path followed by the work as it leaves the needles, for the purpose of applying 30 tension to said work.
